UNITED STATES PATENT OFFICE.

OMER M. GLUNT, OF RUTHERFORD, AND EMIL C. G. MUELLER, OF ELIZABETH, NEW JERSEY, ASSIGNORS TO WESTERN ELECTRIC COMPANY, OF NEW YORK, N. Y., A CORPORATION OF ILLINOIS.

TELEPHONE APPARATUS.

1,120,049.

Specification of Letters Patent.

Patented Dec. 8, 1914.

Application filed August 27, 1913. Serial No. 786,857.

To all whom it may concern:

Be it known that we, OMER M. GLUNT and EMIL C. G. MUELLER, citizens of the United States, residing, respectively, at 5 Rutherford, in the county of Bergen and State of New Jersey, and at Elizabeth, in the county of Union and State of New Jersey, have invented certain new and useful Improvements in Telephone Apparatus, of 10 which the following is a full, clear, concise, and exact description.

This invention relates to telephone transmitters, and more particularly to that type of transmitter which is adapted to be held 15 in the hand of the user. While transmitters of this type may be used wherever a portable transmitter is desirable, the transmitter hereinafter disclosed is particularly adapted for use in telephone systems installed in vehicles to enable the occupant 20 of the vehicle to communicate with the driver thereof. In systems of this character, when installed for instance in an automobile of the limousine type, a receiver located at or near the chauffeur's seat and a 25 hand transmitter located in the tonneau are connected in series with a battery. As the system is in use only a small part of the time, the battery is normally disconnected 30 from the circuit and a switch conveniently located in the handle of the transmitter is provided in order to connect the battery to the circuit while the system is in use.

The invention will be more fully understood by referring to the accompanying drawing, wherein—

Figure 1 is a longitudinal sectional view of the transmitter of the invention taken on the line 1—1 of Fig. 2; Fig. 2 is a similar 40 sectional view taken on the line 2—2 of Fig. 1; and Fig. 3 is a perspective view showing various details in the position which they occupy before assembling.

To a circular plate 1, which forms the 45 mouth-piece of the transmitter, a casing 2 is attached, said plate and casing forming a cylindrical box within which the usual dia- phragm 3, the carbon button 4 and bridge 5 are mounted. The bridge 5 is attached to the 50 plate 1 by means of a plurality of screws 6 so that by removing the plate 1 access may be had for adjusting purposes to the carbon button 4 which is carried thereby.

Secured to the casing 2 by means of rivets

7 is a metal tube 8, which registers with an 55 aperture 9 in the casing. A second metal tube 10 is provided with two integral fingers 11, which are provided with apertures 12 near their upper extremities. The fingers 11 are inserted within the tube 8, and 60 a pin 13 is passed through suitable apertures in the tube 8 and the apertures 12 to secure the tubes 8 and 10 in fixed relation. A tubular handle 14, which may be of wood, 65 hard rubber or other suitable insulating material, surrounds the tube 10 in such a manner that a reduced portion 16 of the handle fits in between the tubes 8 and 10 with the lower end of the tube 8 resting on a shoulder 15. An annular nut 17 is threaded into 70 the lower end of the tube 10 and serves to secure the handle portion 14 to such tube.

The tubes 8 and 10 provide a conduit for the reception of a pair of conductors 18 which are connected to suitable terminals carried by the bridge 5, and a knot 19 in the conductors 18 serves in connection with the nut 17 to prevent the conductors from being pulled out of the handle. Also carried by the bridge 5 are two angular contact springs 20 and 21 which are normally out of contact and are adapted to be placed in contact, to close the circuit of the transmitter, by means of pivoted switch lever 22. The switch lever 22, which is formed 75 of sheet metal, carries at its upper end a contact piece 23 of insulating material and at its lower end a finger piece 26 also of insulating material, and at the central portion thereof are a pair of integral ears 24, 80 each of which is provided with an aperture 25. When in assembled position the switch lever 22 is located within the tube 8, and is pivoted therein by means of the pin 13 which passes through the apertures 25. 85 When in this position the contact springs 21 presses against the contact piece 23, carried by the upper end of the lever 22, and causes the finger piece 26 to project through an aperture 27 in the tube 8.

When the transmitter is in use the speaker grasps the handle 14 and depresses the finger piece 26 with the thumb, thus closing the contacts 20 and 21 and placing battery on the system. Owing to the fact that 105 the speech transmitting elements and the contact springs are all mounted on the plate 1, and the handle and switch lever are se-

cured to the casing 2 by means of a single pin 13, the entire device may be easily assembled. The construction is strong, compact and cheap, and owing to the location 5 of the switch lever the switch may be conveniently operated by the user.

It is obvious that the transmitter element could be replaced by a receiver element and the device used as a hand receiver without 10 departing from the spirit of the invention.

We claim:

1. A hand telephone transmitter comprising a casing having a tubular handle secured thereto, a bridge piece mounted in 15 said casing, a transmitter element and circuit controlling elements carried by said bridge pieces, and a switch operating member mounted in said handle and coöperating with said circuit controlling elements.

20 2. A hand telephone transmitter comprising a cylindrical casing having a tubular handle secured thereto, a bridge piece mounted transversely of said casing, a transmitter element and a pair of contact 25 springs carried by said bridge piece, and a contact closing member mounted in said tubular handle with one end engaging said contact springs and the other end extending through an opening in said handle.

3. A hand telephone transmitter comprising 30 a casing having a transmitter element and a switch mounted therein, a tubular extension on said casing, a tubular member having one end fitted in said tubular extension, an insulating handle surrounding 35 said tubular member, a switch-operating lever in said tubular member, and a pivot pin for said lever serving also to secure said tubular member to said tubular extension.

4. A hand telephone device comprising 40 a cylindrical casing having a telephonic element and a switch therein, a tubular extension on said casing, a tubular member having a pair of upwardly extending fingers adapted to fit within said tubular extension, a switch-operating lever in said tubular member, and a pivot pin for said lever passed through apertures in said tubular extension and said fingers to secure said tubular member to said tubular extension. 45

In witness whereof, we hereunto subscribe our names this 25th day of August A. D., 1913.

OMER M. GLUNT.
EMIL C. G. MUELLER.
